US00D990959S

(12) **United States Design Patent** (10) **Patent No.:** **US D990,959 S**
(45) **Date of Patent:** **** Jul. 4, 2023**

(54) **CUP**

(71) Applicant: **GUANGDONG XINBAO ELECTRICAL APPLIANCES HOLDINGS CO., LTD.**, Guangdong (CN)

(72) Inventors: **Jiangang Guo**, Zhejiang (CN); **Xingmin Zhang**, Guangdong (CN)

(73) Assignee: **GUANGDONG XINBAO ELECTRICAL APPLIANCES HOLDINGS CO., LTD.**

(**) Term: **15 Years**

(21) Appl. No.: **29/813,811**

(22) Filed: **Nov. 1, 2021**

(51) LOC (14) Cl. **07-01**

(52) U.S. Cl. USPC **D7/316**

(58) **Field of Classification Search**

USPC .... D7/316, 392.1, 396.2, 507, 509, 510, D7/511, 512, 513, 514, 515, 523, 536; D9/429, 428, 443, 447, 449, 516 CPC A47G 23/0216; A47G 19/12; A47G 19/2272; A47G 19/2227; A47G 19/2205; A47G 19/22; A47G 23/02; A47G 23/0208; A47G 23/0266; A47G 23/0258; A47G 23/0241; A47J 31/02; A47J 43/27; A47J 31/057; B65D 1/265; B65D 1/36; B65D 2543/00509; B65D 2543/00092
